UNITED STATES PATENT OFFICE.

LEO A. GOEBEL, OF PHILADELPHIA, PENNSYLVANIA.

COMBINED CIGARETTE HUMIDOR AND DELIVERING DEVICE.

1,094,324.

Specification of Letters Patent. Patented Apr. 21, 1914.

Application filed April 29, 1913. Serial No. 764,409.

To all whom it may concern:

Be it known that I, LEO A. GOEBEL, a citizen of the United States, residing at Philadelphia, in the county of Philadelphia and State of Pennsylvania, have invented 5 new and useful Improvements in Combined Cigarette Humidor and Delivering Devices, of which the following is a specification.

An object of the invention is to provide a 10 device to include a humidor for cigarettes to retain the tobacco thereof in a moist and fresh condition, and whereby cigarettes can be individually delivered from the interior of the device.

15 The invention embodies, more particularly, a receptacle adapted to contain cigarettes and constituting a humidor and which is operable in connection with a box-like member supporting the receptacle whereby 20 the cigarettes can be separately delivered from the box to the user.

In the further disclosure of the invention reference is to be had to the accompanying drawings, constituting a part of this specification, in which similar characters of reference denote corresponding parts in all the 25 views, and in which:

Figure 1 is a vertical sectional view of the device, the full lines indicating the normal 30 position of the receptacle and the dotted lines indicating a position of the receptacle when it is desired to deliver a cigarette therefrom. Fig. 2 is a vertical transverse sectional view taken on the line 2—2 in Fig. 35 1; Fig. 3 is a perspective view of the box-like receptacle, parts being broken away to disclose the underlying structure; Fig. 4 is a perspective view of the supporting member adapted to receive the casing therein, 40 parts being broken away to disclose the underlying structure.

Referring more particularly to the views, I provide a box-like receptacle 10 closed on all sides and provided with transverse slots 45 11 in the upper and lower sides thereof. A casing 12 has the upper side thereof open and is adapted to slidably receive the receptacle 10, a supporting plate 13 having the upper edge thereof grooved being arranged 50 centrally in the casing 12 and projecting upwardly from the bottom thereof so that when the receptacle 10 is placed within the container 12 the supporting plate 13 will pass through the slots 11 of the receptacle, 55 as shown in Fig. 1.

Curved apertured partitions 14 are pro-

vided in the receptacle 10, thus forming compartments 15 in which are arranged suitable perforated cylinders 16, containing moistening agents 16a.

Now assuming that the device is in the position shown in Fig. 1 and that a number of cigarettes 17 are contained in the receptacle 10 and lie upon the partition 14, it will be readily apparent that the moistening devices 16 will readily retain the air in the receptacle sufficiently moist so that the tobacco of the cigarettes will not become dry or brittle, but will retain its flavor and be soft and pliable. Now when it is desired to deliver a cigarette to the user, the receptacle 10 is grasped between the fingers of the user, suitable thumb grips 18 being provided on the receptacle for this purpose, and an upward pull is exerted on the receptacle, thus sliding the receptacle upwardly and outwardly from the casing 12. Now when the upper curved edge of the supporting plate 13 is approached by the upper faces of the partitions 14, due to the raising of the receptacle 10 in the casing 12, it will be readily apparent that one of the cigarettes on the partition will gravitate on to the curved upper face of the supporting plate, and, if the receptacle 10 is now permitted to drop back into the casing 12, the cigarette will be exposed adjacent the upper face of the receptacle when the receptacle reaches its normal position within the casing inasmuch as the return of the receptacle within the casing brings the upper face of the supporting plate 13 within the slot in the upper face of the receptacle 10, as shown in Fig. 1; and, therefore, the cigarette which the user desired will be exposed and can be readily removed from the plate 13.

When it is desired to fill the receptacle 10 with cigarettes it is necessary only to raise the same a sufficient distance to open the upper slot 11 and which is normally closed 100 by the supporting plate 13, and the cigarettes can then be dropped into the receptacle to lie upon the partitions 14 where the tobacco of the cigarettes will be kept moist and fresh. The side walls of the casing 12 105 are provided with cut away portions 19 to expose the thumb grips 18 of the receptacle 10 so that the operator can readily grip the receptacle and lift the same relatively to the casing 12 in order that the partitions will 110 be brought nearer to the curved upper face of the supporting plate so that the cigarette

will gravitate on to the upper face of the plate and be supported thereby upon the return of the receptacle within the casing 12.

The device described is of simple and durable construction and can be made of either wood or metal. Furthermore the device not only provides a humidor but also presents a structure whereby individual cigarettes can be easily and quickly delivered to the user, it being understood that one cigarette is delivered each time that the receptacle 10 is partially removed from the casing 12.

Having thus described my invention, I claim:

In a device of the class described, the combination with a receptacle having transverse slots in the upper and lower faces thereof, of a casing adapted to slidably receive the receptacle, a supporting plate carried by the casing and projecting through the slots in the receptacle, with the upper edge of the

supporting plate normally lying flush with the upper face of the receptacle, curved apertured partitions within the receptacle to support cigarettes which will normally lie against the sides of the supporting plate and whereby a single cigarette will be delivered to the curved face of the supporting plate when the receptacle is slid upwardly and partially out of engagement with the said casing, apertured cylinders carried within the receptacle adjacent the curved partitions therein, and moistening agents carried within the said cylinders for supplying moisture to the tobacco of the cigarettes on the said partitions.

In testimony whereof I affix my signature in presence of two witnesses.

LEO A. GOEBEL.
